1 Claim. (Cl. 307—88.5)

This invention relates to a circuit protecting a transistor type direct current constant voltage device from an overcurrent by using a silicon controlled rectifier. In general, a short circuit of a load circuit and an overcurrent generated by an error of connection of a load exert significant ill influences on a transistor type constant voltage device.

The object of the present invention is to provide a novel protection circuit in which an overcurrent is cut off from a load circuit instantaneously and automatically, and said status is maintained unless a push-button switch S.W. on the output side of the transistor type direct current constant voltage device is pushed.

The object and advantage of this invention will become readily apparent from the following detailed description, in which:

The drawing is a view showing one embodiment of a protection circuit in accordance with this invention.

In the drawing, CVU is a transistor type direct current constant voltage device and E₁ is a supply electric power source of said transistor type direct current constant voltage device CVU.

To positive terminal 1 on the output side of said transistor type direct current constant voltage device CVU, a load circuit in which a silicon control rectifier SCR₁ is serially connected to a load RL and a by-pass circuit in which a silicon control rectifier SCR₂ is connected serially to a by-pass resistor R_B of the load are connected. An overcurrent detection circuit is inserted between said two circuits and the negative terminal on the output side of the transistor type direct current constant voltage device CVU consists of a voltage detection resistor R₁ for gating SCR₂ connected to the negative pole of SCR₁ and a voltage detection circuit for gating SCR₁ which is connected serially to a resistor R₁ and to the negative pole of SCR₂ at point 4, and said voltage detection circuit for gating said SCR₁ consists of connecting a resistor R₃ to the positive terminal of a reference electric power source E₂ and by connecting parallelly a resistor R₂ thereto.

The connection point 5 of said resistor R₂ and said resistor R₃ is connected to the negative terminal 2 on the output side of the transistor type direct current constant voltage device CVU and the gate circuit of SCR₁, and the gate circuit of said SCR₁ consists of by connecting serially a gate protection resistor R₄ and a silicon diode D₁. The gate circuit of SCR₂ consists of a gate protection resistor R₅ and a silicon diode D₂ and is connected to the negative terminal 3 of SCR₁. C is a condenser; it is inserted between the anodes of SCR₁ and SCR₂ and assists the ignition of a gate of SCR₂.

Next, we will explain the operation of the protection circuit of a transistor type direct current constant voltage device in accordance with the present invention.

Supposing the electric current generated in the closed circuit formed by resistor R₂, resistor R₃ and reference electric current source E₂, by only said reference electric current source E₂ is I₃, the voltage V₂ between points 4 and 5 will be as follows:

$$V_2 = I_3 R_2$$

2

If said voltage V₂ is a sufficient value to ignite SCR₁, since a voltage is being applied to the gate circuit of SCR₁ in the conducting direction, SCR₁ is ignited and a load electric current I₁ flows.

Said load electric current I₁ flows through resistor R₁, resistor R₂, reference electric power source E₂ and resistor R₃ to the negative terminal on the output side of the transistor type direct current constant voltage device CVU.

Accordingly, due to said load electric current I₁, the voltage V₁ between the points 3 and 4 will have a value obtained by multiplying the sum of said load electric current I₁ and the gate electric current of SCR₁ by the resistor R₁, and the voltage V₂ between the points 4 and 5 will be as follows.

$$V_2 = \left(I_3 - \frac{R_3}{R_2 + R_3} I_1 \right) R_2$$

If said load electric current I₁ increases, the voltage V₂ between the points 4 and 5 will further drop, and if said load electric current I₁ exceeds.

$$\left(1 + \frac{R_2}{R_3} \right)$$

I₃, V₂ will become a negative voltage as the polarity reverses, and an extinction voltage of arc will be sent into the gate of SCR₁.

On that occasion, the voltage V₁ between the points 3 and 4 will become nearly equal to the product of said load electric current I₁ times said resistor R₁. If said load electric current I₁ increases further and reaches the largest rated load electric current I₁₀, the voltage V₁ between the points 3 and 4 will become as follows:

$$V_1 = I_{10} R_1$$

If a resistor R₁ is chosen in such manner that said voltage will become equal to an igniting voltage of arc of SCR₂, since a voltage in the conductive direction is being sent into the gate circuit of SCR₂, it will be ignited instantaneously, the by-pass circuit will be made conductive and a by-pass electric current I₂, which is a little smaller than the largest load electric current will flow. In that instance, since an extinction voltage of arc is being sent to SCR₁, it will be assisted by condenser C and will extinct immediately and cut off the load circuit.

Like this, if said load electric current I₁ reaches the largest load electric current I₁₀, SCR₂ will instantaneously ignite and complete the by-pass circuit, extinct SCR₁ and cut off the load circuit, but, when this status is attained, the gate circuit of SCR₁ is held in a negative voltage and will not be ignited again.

Also, though the gate voltage V₂ of SCR₂ will almost become to be a zero voltage, as long as SCR₁ does not ignite, SCR₂ will never be extinguished due to the operation of the condenser C and the characteristics of the silicon control rectifier.

Accordingly, as long as the transistor type direct current constant voltage device CVU is not cut off, it will never be switched from a by-pass circuit to a load circuit.

Incidentally, though it is desirable that a by-pass electric current I₂ is equal to the largest rated load electric current I₁₀, as far as the characteristics of a silicon control rectifier permits, it is economical that a by-pass electric current I₂ is smaller than the largest load electric current I₁₀.

As mentioned above, since the protection circuit of the transistor type direct current constant voltage device in accordance with the present invention will, if an overload electric current flows into a load circuit, cut off instantaneously the load electric current of the load circuit and switches to a by-pass circuit, it will protect safely the transistor type direct current constant voltage device

from an overload electric current generated by a short-circuit or an error of connection of load.

While a preferred embodiment of the present invention is disclosed, it is recognized that the scope of the present invention is not limited thereto and it is therefore intended that the scope of the present invention be defined by the scope of the appended claim.

What is claimed is:

A circuit for protecting a source of supply voltage from excessive current flow comprising
 10 a pair of terminals arranged to be connected to the output of the voltage source,
 a load circuit including a load device, a first silicon controlled rectifier, and first and second resistors connected in series between said terminals,
 15 a by-pass circuit including a by-pass resistor, a second silicon controlled rectifier, and said second resistor connected in series between said terminals,
 a first gate circuit including a first diode connecting said first and second resistors between the gate and 20 cathode of said first rectifier,
 a source of reference voltage connected in parallel with said second resistor and poled to apply a turn-on voltage to said first rectifier by way of said first gate circuit to render said first rectifier conductive to per- 25

mit current to flow in said load circuit between said terminals,

said first and second resistors being so connected as to apply a turn-off voltage to said first rectifier by way of said first gate circuit when the value of the current flowing in said load circuit exceeds a predetermined value, and

a second gate circuit including a second diode connecting said first resistor between the gate and cathode of said second rectifier to apply thereto a turn-on voltage to render said second rectifier conductive when said current value exceeds said predetermined value,

the conduction of said second rectifier cooperating with said turn-off voltage to render said first rectifier non-conductive to reduce the flow of current between said terminals.
